UNITED STATES PATENT OFFICE.

EDWARD B. HESS, OF ORLANDO, FLORIDA, ASSIGNOR TO ROYAL TYPEWRITER COMPANY, INC., OF NEW YORK, N. Y., A CORPORATION OF NEW YORK.

TYPEWRITING MACHINE.

Application filed September 1, 1926. Serial No. 133,002.

This invention relates to a construction in which a paper apron is provided with a scale in its upper edge and a swinging paper table is movable to a position in which the lower edge of the same will contact with the upper edge of the paper table and the surfaces of the two will form a continuous plane surface for the paper introduced into the machine. The margin stop bar is located behind the paper apron and paper table and the margin stop indicators lie immediately adjacent the paper scale. When the paper table is in its forward or operative position, the stops and bar are hidden from view. When the paper table is moved rearwardly the stop bar is uncovered and the stops may be readily adjusted by reference to the scale on the upper edge of the paper apron.

This construction enables a very compact arrangement of parts and provides for an easy and accurate adjustment of the margin stop as desired. The invention is broadly independent of any specific form of paper table, paper apron or margin stop. It may be embodied in constructions differing quite widely from the one illustrated in connection with this application.

Further details of the invention will be apparent from the following description and the appended claims.

In the drawings:

Figure 1 is a fragmentary front view of the platen, paper apron and paper table with a portion of the table broken away to show the margin stop underlying the same.

Figure 2 is a fore and aft section with the paper table in its operative position.

Figure 3 is a front view with the paper table moved to its rear position uncovering the margin stop for adjustment.

The drawings show a portion of the side frame of a carriage A supporting a platen B, a tabulating stop bar C and a margin stop bar D. This margin stop bar is toothed in the usual manner and supports margin stop E which may be adjusted to any desired position thereon. So far as the invention is concerned these elements may be of any old or desired form.

A paper apron 1 passes partly around the platen and has its upper edge terminating in a plane slightly below the top of the platen. The rear edge of the paper table is shown as recessed and a scale 2 which extends from side to side of the apron is supported in said

recess. This is for the purpose of having a smooth surface for the front side of the paper table. It is obvious that the scale may be engraved or otherwise formed directly on the surface of the paper apron without departing from the invention.

Each margin stop has an indicator 3 which is adjustably supported upon the stop by means of a screw 4 passing through a slot 5 in the indicator member. This indicator is located immediately adjacent the scale as is apparent from Figures 1 and 3 and the stop can therefore be adjusted readily with reference to the scale when the paper table is moved to its rear position.

A paper table 6 is supported by arms 7 which have offset portions terminating in extensions 8 parallel to the arm 7 which is preferably mounted just outside the side frame bars A of the carriage to turn about the axis of the tabulating stop bar D. These arms may, however, be pivotally supported on the carriage frame in any desired manner. A spring 9 at one or both sides of the carriage has one end fastened to a pin or stud 10 on the carriage frame and its other end to a similar stud or pin 11 on the portion 8 of the apron supporting arm. This spring is so located with reference to the axis about which the paper table turns that it tends to retain the paper table in either its operative position shown in Figure 2 or its rear inoperative position illustrated in Figure 3.

The paper table may have a rolled edge 12 at its upper edge and a right angular portion 12' at its lower edge which will abut directly against the edge of the scale 2 or the upper edge of the paper apron. On the back side of the paper table 6 near the center thereof is an angular bracket 13, which has a portion 14 spaced from the paper table and an extension arm or paper holding finger 15 is pivotally mounted by a screw 16 on the portion 14 of said bracket. A spring washer 17 is interposed between the head of the screw and the paper finger and tends to hold the latter in any adjusted position.

A stop 18 on said bracket cooperates with the arm 15 on one side or the other of the screw 16 for the purpose of limiting the movement of the paper finger 15 in either direction. When this finger is in operative position, it will extend upwardly and rearwardly from the paper table as shown in

Figure 2 and when it is not desired to use the same, it is moved to the position shown in Figures 1 and 3 wherein it lies behind the paper table and is hidden from view.

It will be apparent that the invention discloses a simple and efficient construction whereby the carriage stops may be located immediately behind the paper table and paper apron and immediately adjacent the upper edge of the paper apron which carries a scale and in which the paper table may be moved to an inoperative position for the purpose of uncovering the margin stop, which can then be quickly and easily adjusted by direct reference to the scale on said paper apron. It is also apparent that the precise form of the elements illustrated in this embodiment of the invention may be modified without in any way changing the character of the invention. The invention consists primarily in the broad relationship of the various elements rather than in any specific construction of the separate elements, although from a more narrow point of view further specific features do cooperate with each other. In general it is to be understood that the invention is to be regarded as limited only by the scope of the appended claims.

30 I claim as my invention:

1. In a typewriting machine, the combination of a paper apron, a scale extending across the front of said apron at its rear top edge, a pivoted paper table having its lower edge abutting the upper edge of the paper apron when the parts are in normal position, a stop bar immediately behind and closely adjacent the upper edge of the paper apron, a stop carried thereby and having an indicating portion registering with the scale, the relative position of the parts being such that when the paper table is swung to inoperative position the stop may be set at any desired point by direct comparison of the indicating portion with the scale.

2. In a typewriting machine, the combination of a paper apron, a scale extending across the front of said apron at its rear top edge, a pivoted paper table having its lower edge abutting the upper edge of the paper apron when the parts are in normal position, a stop bar immediately behind and closely adjacent the upper edge of the paper apron, a stop carried thereby and having a horizontally arranged indicating portion registering with the scale, the relative position of the parts being such that when the paper table is swung to inoperative position the stop may be set at any desired point by direct comparison of the indicating portion with the scale.

3. In a typewriting machine having a carriage provided with the usual platen,

combination of means for supporting a letter space scale in the rear of said platen, a 65 stop bar located immediately behind and adjacent said scale, a stop carried thereby and having an indicating portion registering with the scale, and a pivoted paper table normally hiding the stop from the view of 70 the operator, the relative position of the parts being such that when the paper table is swung to inoperative position the stop may be set at any desired point by direct comparison of the indicating portion with the 75 scale.

4. In a typewriting machine having a carriage provided with the usual platen, the combination of means for supporting a letter space scale in the rear of said platen, a 80 stop bar located immediately behind and adjacent said scale, a stop carried thereby and having a horizontally arranged indicating portion registering with the scale, and a pivoted paper table normally hiding the stop 85 from the view of the operator, the relative position of the parts being such that when the paper table is swung to inoperative position the stop may be set at any desired point by direct comparison of the indicating portion 90 with the scale.

5. In a typewriting machine having a carriage provided with the usual platen, the combination of means for supporting a letter space scale in the rear of the platen, a 95 margin stop bar on said carriage immediately behind and adjacent said scale, a stop carried thereby and having an indicating portion registering with the scale, and a 100 movable paper table normally positioned between the scale and the stop and concealing the latter from the operator, the movement of said paper table permitting the stop to be set at any desired letter space position 105 by direct comparison of the indicating portion with the scale.

6. In a typewriting machine having a carriage provided with the usual platen and paper apron, the combination of a pivoted paper table having its lower edge abutting the upper edge of the paper apron when the parts are in normal position, a stop bar immediately behind and closely adjacent the upper edge of the paper apron, a fixed scale 110 in front of the paper apron but close to said stop bar, and an adjustable stop carried by said bar and having an indicating portion 115 registering with the scale, the relative position of the parts being such that when the paper table is swung to inoperative position 120 the stop may be set at any desired point by direct comparison of the indicating portion with the scale.

In testimony whereof, I have hereunto subscribed my name.

EDWARD B. HESS.
